(57) CLAIM

The ornamental design for an optical scanner, as shown in the accompanying drawings and described above.

DESCRIPTION

FIG. 1 is a front, upper right perspective view of an optical scanner in accordance with the present invention.

FIG. 2 is a front, lower left perspective view of the optical scanner of FIG. 1.

FIG. 3 is a front elevation view of the optical scanner of FIG. 1.

FIG. 4 is a rear elevation view of the optical scanner of FIG. 1.

FIG. 5 is a right elevation view of the optical scanner of FIG. 1.

FIG. 6 is a left elevation view of the optical scanner of FIG. 1.

FIG. 7 is a top plan view of the optical scanner of FIG. 1; and,

FIG. 8 is a bottom plan view of the optical scanner of FIG. 1.

The broken lines depict unclaimed features of the optical scanner that are shown for illustrative purposes and form no part of the design claim. The dot-dash line indicates a boundary of the claimed design.
